BURNER

Herbert J. Long, Springfield, and Hans Albrecht, West Springfield, Mass., assignors to United American Bosch Corporation, Springfield, Mass., a corporation of New York

Application October 29, 1936, Serial No. 108,126

2 Claims. (Cl. 158—115)

This invention relates to gas burners and particularly burners adapted for use as pilot burners. In gas appliances, such as water heaters, the burners are commonly provided with 5 a pilot flame adjacent thereto and usually means are provided for cutting off the fuel supply in case the pilot becomes extinguished. In such constructions it is common to associate a thermostatic device with the pilot burner in such a manner that when the pilot is extinguished the thermostatic device closes a valve controlling the main fuel supply. For the pilot flame, both Bunsen burners and luminous flame burners have been used. The Bunsen type, however, has the 15 disadvantage that if the quantity of gas supplied to the burner is small the mixture may be ignited in the burner tube and thus create a flame adjacent the primary air orifices. When this happens there is no flame at the burner tip for igniting the main burner but the heat generated 20 by the combustion in the burner tube is still sufficient to maintain the temperature of the thermostat and hold it in open position the valve controlling the main burner. It therefore happens that this type of pilot burner does not always afford the protection against the flow of fuel to the main burner in case the latter is extinguished at a time when there is no flame at the pilot tip. On the other hand the luminous flame type of 25 burner has the disadvantage that the flame projects for a considerable distance from the burner tip before it meets with sufficient air to effect complete combustion. For this reason there is little heat at the burner tip in proportion to the 30 gas consumed and a relatively high rate of gas consumption is required to insure sufficient heat adjacent the burner tip to actuate the thermostatic device.

It is a primary object of the present invention 35 to provide a burner avoiding the above mentioned defects, which possesses the advantages of the Bunsen type in that a small blue flame is provided adjacent the burner tip, while also possessing the advantages of the luminous flame burner 40 in that there is no mixing tube in which a mixture of gas and air might become ignited. To this end we provide a burner in which the mixing of gas and air occurs entirely at the burner tip providing a small blue flame at a relatively low rate 45 of gas consumption which, however, insures ignition of the main burner jets and at the same time provides sufficient heat immediately adjacent the pilot burner to insure the actuation of the thermostatic device.

50 It is a further object of this invention to pro-

vide a pilot burner which consumes far less gas than has previously been required by such burners and which is therefore more economical in operation.

The above and other objects and features of 5 this invention will in part be obvious to those skilled in the art and in part be more fully set forth in the following detailed description taken in conjunction with the accompanying drawing 10 in which:

Fig. 1 is a longitudinal section with parts in side elevation through a burner chamber provided with a pilot constructed in accordance with this invention; Fig. 2 is a detail on an enlarged scale of a pilot burner shown in Fig. 1; Fig. 3 15 shows, in section with parts in side elevation, a modified form of a pilot burner; and Fig. 4 is a detail on an enlarged scale of the pilot burner shown in Fig. 3.

In the drawing, reference numeral 1 indicates 20 a burner cup in which are main burners 2 which in the form shown are of the Bunsen type but which may be of any type. A pilot burner 3 is disposed centrally of the main burners 2 in a position to ignite each jet of the main burners. 25

Gas is supplied to both pilot and main burners by way of a pipe 4 which opens into a tube 5 projecting centrally into the cup 1 and fastened thereto by means of screw bolts 6. The tube 5 has an enlarged upper end into which a bushing 7 is threaded. A valve 8 is adapted to control the opening at one end of the bushing and a thermostat housing 9 closes the opposite end. Above the valve 8 the bushing 7 is provided with lateral openings 10 which provide communication between the interior of the bushing 7 and an annular chamber 11 provided in the upper end of the tube 5. A connection 12 passes through the enlarged portion of the tubular member 5 to communicate with the annular chamber 11 and 40 leads to the valve chamber 13 of a thermostatically controlled valve 14. A thermostat 15, which in the case of a water heater is positioned in the storage tank or hot water connection of the heating system or in the case of an oven is 45 responsive to the temperature thereof, controls the valve 14. From the control device gases pass by way of connections 16 to the manifold 17 which supplies the gas jets 2. A portion of the gas which passes through the valve 8 flows upwardly 50 through the bushing 7 into the housing 9 of the disk thermostat 18. Openings 19 in the disk 18 permit the gas to flow from the lower portion of the housing 9 to the upper portion. A tube 20 mounted upon the upper end of the thermostat 55

housing 9 has a longitudinally extending passage 21 which communicates with the interior of the housing 9 by way of a passage 22 controlled by an adjusting screw 23. A cap 24 is mounted upon the upper end of the tube 20 closing the longitudinal bore 21. Angular passages 25 extend from the bore 21 to the outer surfaces of the tube 20 providing jet orifices. The passages 25 are so directed toward the lower face of the cap 24 that the jets, issuing from these passages impinge against the lower surface of the cap and spread outwardly therefrom. The cap is positioned sufficiently close to the jet orifices so that the gases are still moving at relatively high velocity when they impinge upon the under surface of the cap. A flange 26 projects downwardly from the outer rim of the cap deflecting the gases flowing along the under surface thereof toward a baffle member 27.

20 The operation of this form of the device is as follows. Gas supplied from the pipe 4 passes upwardly through the tubular member 5, the valve 8 and thence by way of openings 10 and connection 12 to the thermostatic valve 14. A portion of the gas passing through valve 6 flows upwardly through the bushing 7 into the thermostat housing 9 and through the openings 19 in the thermostat disc 18. It thence passes upwardly through the passages 21 and 22 in the tubular member 20 and to the jet passages 25. A plurality of such passages is provided, three being sufficient in a burner of the size shown. Each passage is directed upwardly to the under surface of the cap 24 so that the jets from the passages impinge against the under surface of the cap at an angle of 45°. It will be noted that the jet passages 25 are designed to give the gas issuing therefrom a relatively high velocity. This velocity is such, and the jets are so constructed, that there is little opportunity for combustion to occur while the gas passes from the jet orifice to the surface of the cap. The high velocity jet tends to entrain air from the surrounding atmosphere and this is admixed with the gas upon impingement against the under surface of the cap. It will be noted that the cap is placed in close proximity to the jet orifices, the vertical distance between the jet orifice and the under surface of the cap is of the order of $\frac{1}{8}$ of an inch, though on the enlarged scale of Fig. 2 this distance appears much greater. The gas therefore still possesses considerable velocity upon impinging against the under surface of the cap, which velocity is too great to permit the combustion of the gas and air during the mixing process. As the mixture flows outwardly toward the circumference of the cap, it is deflected downwardly by the flange 26 and spread in the form of a thin sheet into the surrounding air. In this manner the gas is thoroughly mixed with the air in a small space immediately surrounding the burner cap, and because it is well mixed with the entrained air and well diffused in the air immediately surrounding the burner tip, it burns with a blue flame similar to a Bunsen flame. It is impossible for the combustion to flash downwardly through the tube 20 and burn adjacent the thermostat because no air is mixed with the gas until it leaves the jet orifice. When the thermostatically controlled valve 14 shuts off the flow of gas to the main burner, the valve 8 remains open

supplying gas to the pilot burner. Heat generated by this burner is conducted downwardly through member 20 to the housing 9 and thus to disc thermostat 18. Should the pilot flame become extinguished, the thermostat will cool quickly to close the valve 8.

The form shown in Fig. 4 is similar to the form above described, but is more particularly adapted for use in conjunction with burners wherein it is desired to position the pilot horizontally. In this form gas is supplied to the main burners 28 from a gas manifold 29, the flow to which may be controlled in the same manner as has been described in connection with Fig. 1. The pilot burner 30 in this instance consists of a tubular member 31 which is mounted on a thermostat housing 32 in a manner analogous to the mounting of tube 20 upon housing 9 in the form shown in Fig. 1. The tube 31 carries at its outer end a flange 33, and is internally screw threaded to accommodate external screw threads upon a burner tip member 34. The burner tip 34 has a central passage 35 extending partially therethrough, and the jet passages 36 afford communication between the central passage 35 and the atmosphere. The jet passages 36 are directed toward flange 33 and the open ends thereof are sufficiently close to the surface of said flange to insure that the gases issuing from the jets retain a high velocity until they impinge against the latter.

The operation of this latter form of the device is analogous to the operation of the form previously described in that the gases issuing at high velocity from the jet passages 36 entrain a small quantity of air in the course of their flow from the outer end of these passages to the flange 33. Upon impinging against this flange, the entrained air is mixed with the gases before material combustion can take place, and the gas is therefore in condition to burn with a blue flame as the gaseous mixture is deflected outwardly into surrounding atmosphere by the flange 33.

Having thus described our invention, what we claim is:

1. A burner comprising a tubular member having a gas passage extending longitudinally thereof, a cap mounted on said tubular member, an angular passage forming a gas jet having one end opening into said longitudinal passage and the opposite opening to the atmosphere at a point immediately adjacent to and directed toward one of the faces of said cap, means to supply gas unmixed with air through said passage and jet and a flange extending from one face of said cap, whereby gas from said jet is first deflected outwardly by said face and thence deflected in a direction at an angle thereto by said flange.
2. A gas pilot burner having a plurality of spaced jet passages of small diameter relative to their length opening to the atmosphere, means for supplying gas unmixed with air to said passages, and a deflecting member immediately adjacent the openings of said jet passages and positioned angularly thereto whereby gas issuing from each of said jets is completely surrounded by air which is entrained thereby for admixture and combustion therewith upon impinging against said deflecting member.
